UNITED STATES PATENT OFFICE.

SAMUEL E. PORTER AND ALBERT H. HARBAUGH, OF CASSTOWN, OHIO.

ADJUSTABLE HEADLIGHT.

No. 876,488.

Specification of Letters Patent.

Patented Jan. 14, 1908.

Application filed February 5, 1907. Serial No. 355,962.

To all whom it may concern:

Be it known that we, SAMUEL E. PORTER and ALBERT H. HARBAUGH, citizens of the United States, residing at Casstown, in the county of Miami and State of Ohio, have invented new and useful Improvements in Adjustable Headlights, of which the following is a specification.

Our invention relates to adjustable head lights and particularly such head lights as are used upon cars, locomotives and the like.

In devices of this class it is desirable that in going up and down grades, or around curves, the head-light be directed in such a direction as will throw the most light upon the road.

The object of this invention is to so arrange the head-light that it can be easily adjusted for all conditions of travel.

In order that our invention may be more readily understood reference is had to the accompanying drawing forming part of this specification, and in which,

Figure 1 is a plan view, and Fig. 2 a side elevation of our improved device as attached to an ordinary car.

Referring to the drawings in detail, A represents any suitable form of head-light which may be of any well known construction and does not constitute any part of our invention.

B designates the dash-board of a car and C the platform.

The head-light A is mounted upon a bracket P pivoted at D to an arm N, which in turn is pivoted at E to a lug or other support attached to the car or vehicle. The pivot D allows the head-light to swing in a horizontal plane, while the pivot E permits of movement in a vertical plane.

In order to control the positions of the light, we mount on the car platform or in any other suitable manner, two levers F and G by means of pivots as H which allow said levers to swing in a vertical plane. Adjacent to the levers are arranged two arc-shaped racks I and K adapted to coöperate with a locking bolt L carried by the levers and controlled by means of a handle M as will be understood.

A rod O passes through a suitable slot in the dashboard and connects the lever G with the head-light at one side of the pivot D. When this lever is pulled back the light will be swung to the right into the position shown in

dotted lines at A', Fig. 1. A rod Q connects the lever F with a lug or eye attached to the arm N, and when this lever is swung backward on its pivot the head-light will be thrown up into the position shown in dotted lines at A², Fig. 2. A reverse movement of the levers will, of course, throw the head-light in the opposite direction. It will thus be seen that by means of manipulating these two levers the head-light may be turned up or down or to either side in any desired direction and the locking pawl L will hold the light in any position in which it may be set as will be well understood. By this simple arrangement we are enabled to produce a head-light-structure which is very simple in operation and very effective in throwing the light just where it is needed.

Although we have shown our invention as applied to a car platform, it is obvious that it can be employed with equal facility in connection with automobiles, locomotives, or any other type of vehicle whatever.

Having thus described our invention, we claim as new and desire to secure by Letters-Patent:

1. The combination with a vehicle body, of a fixed support, an arm having one end vertically bifurcated to straddle the support and its other end horizontally bifurcated, a head light pivoted in the latter bifurcation, a lever operatively connected with the head light, and a second lever connected with the arm.

2. The combination with a vehicle body, of a fixed support, an arm having one end vertically bifurcated to straddle the support and pivotally connected thereto, and its other end bifurcated, a head light having an extension pivoted in the latter bifurcation, a lever operatively connected with the head light to move it in arcs parallel with the plane of the vehicle body, a second lever operatively connected with the arm to move the latter through planes at right angles to the vehicle body, and means for locking either of the levers at any desired adjustments.

In testimony whereof, we affix our signatures in presence of two witnesses.

SAMUEL E. PORTER.

ALBERT H. HARBAUGH.
